Primary Examiner — Nicole C Shiflet*Assistant Examiner* — Danielle Nichole Bowly(74) *Attorney, Agent, or Firm* — Oliff PLC(57) **CLAIM**

The ornamental design for a textile printing machine, as shown and described.

DESCRIPTION

FIG. 1 is a perspective view of the textile printing machine; FIG. 2 is a front elevational view thereof; FIG. 3 is a rear elevational view thereof; FIG. 4 is a left-side elevational view thereof; FIG. 5 is a right-side elevational view thereof; FIG. 6 is a top plan view thereof; and, FIG. 7 is a bottom plan view thereof.

The evenly spaced broken lines depict unclaimed parts of the textile printing machine and form no part of the claimed design.
